Primary Examiner — Lakiya Rogers*Assistant Examiner* — Harold E Blackwell, II(74) *Attorney, Agent, or Firm* — Michelle E. Carey; Telekta Law, P.S.**CLAIM**

The ornamental design for a spout, as shown and described.

DESCRIPTION

FIG. 1 is an isometric environmental view of the spout, showing my new design;

FIG. 2 is a front plan view of the spout;

FIG. 3 is a right side plan view thereof;

FIG. 4 is a rear plan view thereof;

FIG. 5 is a top plan view thereof;

FIG. 6 is a bottom plan view thereof; and

FIG. 7 is a cross-sectional plan view thereof.

The broken line showing of the spout illustrates the environment of the claimed design and forms no part thereof.
